DISPENSING DEVICE

Joseph A. Diemer, New York, N. Y.

Refile for abandoned application Serial No. 48,558,
November 6, 1935. This application April 5,
1938, Serial No. 200,244

3 Claims. (Cl. 312—70)

This application is refiled as a substitute for abandoned application, Serial No. 48,558, filed November 6, 1935.

This invention relates to article dispensing devices and has for its general object the provision of a simple and economical device particularly adapted for the dispensing of eating utensils, such as knives, forks and spoons.

A more specific object of my invention is to provide a dispensing cabinet in which the various utensils may be contained in an orderly and sanitary condition, from which cabinet the utensils may be readily dispensed at will by the convenient operation of a plunger.

Another object of my invention resides in providing a novel arrangement of mechanism by which articles having an irregular or serpentine contour, such, for example, as forks and spoons, may be efficiently ejected to a suspended position so as to be readily grasped by the user, as required.

The invention will be fully and comprehensively understood from a consideration of the following detailed description when read in connection with the accompanying drawing which forms part of the application, with the understanding, however, that the improvement is capable of extended application and is not confined to the exact showing of the drawing nor to the precise construction described and, therefore, such changes and modifications may be made therein as do not affect the spirit of the invention nor exceed the scope thereof as expressed in the appended claims.

In the drawing:

Fig. 1 is a perspective view of a table utensil dispensing cabinet embodying the features of my invention.

Fig. 2 is a fragmentary vertical sectional view illustrating the mode of operation of my dispensing device; and

Fig. 3 is a horizontal section thru the hopper for containing the articles to be dispensed, taken on line 3—3 of Fig. 2.

Referring now to the drawing for a more detailed description thereof, the numeral 4 indicates the dispensing cabinet embodying my invention, which is provided with a hingedly mounted cover 5 at the top or side thereof. The interior of the cabinet 4 is divided into a plurality of vertical compartments by partitions 6, each compartment being intended to contain respectively the required knives, forks, spoons, etc., or other article to be dispensed.

In the front wall of the cabinet 4 are arranged suitable indicia by which to identify the contents of each compartment. Preferably, I employ

a series of glass covered display cases 7, one for each of the mentioned compartments, in which cases are displayed the article corresponding to the contents of the particular compartment in which it appears. In each of the compartments comprising my dispensing cabinet is removably supported a hopper or vertical chute 8 suspended for convenient removal as by the brackets 9. The function of the hopper 8 is to retain in a vertical stack the articles to be dispensed, such as the spoons illustrated.

The preferred embodiment of a suitable hopper comprises opposed vertical guide channels 10 and 11 arranged to contact corresponding end portions of the articles to be dispensed. The guide channels 10 and 11 are connected into a composite structure by the side panels 12, which panels are omitted at the top and bottom of the hopper 8 so as to facilitate the loading of same. At the bottom of the forward guide channel 10 is provided a horizontal shelf 13 extending inwardly, against which the forward end of the lowermost article may rest in support of the entire stack. The rear guide channel 11 is likewise provided with a shelf 14, which shelf is preferably resilient in structure and bent downwardly, as shown, for the purposes hereinafter described. In the front wall of the channel 10 just above the shelf 13 is cut an aperture 15 of a size ample to permit the entrance of an ejecting plunger 16 into the hopper 8. The rear wall of the channel 11 is provided with an aperture 17 of a size to permit only the passage thru same of the lowermost article.

The plunger 16 is mounted for axial sliding on the front of the cabinet 4, being supported on a slide plate 18 and a guide tube 19. The tube 19 is rigidly attached to the plate 18, which plate is secured to the front wall of the cabinet 4 as by the screws 20. Suitable means for urging the plunger 16 outwardly is provided, such as the coil spring 21 surrounding the plunger, which spring is backed by the plate 18 to press against a collar 22 secured to the plunger 16.

The upper portion of the end of the plunger 16 projecting into the cabinet 4 is provided with a bevel 23. The normal position of the plunger 16 is indicated by dot and dash outline, in which position the lowermost article is resting on the shelf 13. When the article is to be dispensed the plunger 16 is manually pressed inwardly against the force of the spring 21, whence the inner end 24 of the plunger engages with the forward end of the article. Coactively with this operation, the front end of the article just above the lowermost one is engaged on the bevel 23, 55

the inward motion of which causes the forward end of the entire stack of articles to be raised substantially so that the weight thereof is appreciably released from the lowermost article, which is simultaneously slid backwardly so that its end passes thru the aperture 17 and the article temporarily assumes the position shown in dotted outline in Fig. 2.

As soon as the front end of the lowermost article is pushed off the forward shelf 13 the article is permitted to take the angular suspended position shown in full line, in which position the article is frictionally engaged between the resilient shelf 14 and the rear end of the remaining articles in the stack. The resilience of the shelf 14 provides a cushioning effect for the article as it lowers to its angular position upon release from the front shelf 13. In this angular position the article required may be readily grasped by the hand inserted into a suitable opening 25 out in the front wall of the cabinet 4.

It will be observed that my invention assures sanitary protection for eating utensils as well as convenient means by which each utensil as required may be readily dispensed from the cabinet by a simple operation of the plunger 16 and a subsequent withdrawal of the article from the cabinet.

I claim:

30. 1. A device of the character described comprising a cabinet, a magazine removably supported in said cabinet and adapted to retain a series of articles vertically stacked therein, spaced means adjacent the bottom of said magazine for supporting the articles at their ends, a resiliently mounted plunger carried on said casing and disposed adjacent the bottom of said magazine so as to push the bottom article from one of the supporting means, said magazine comprising 40 spaced vertical guide channels including end

walls terminating above the supporting means to present apertures, through one of which an end of said article extends when the article is pushed off one of the supporting means, said plunger operating in said other aperture.

5

2. A device of the character described comprising a magazine substantially open at the bottom in which articles may be stacked vertically, a pair of spaced shelves projecting substantially into said magazine upon which the ends of the lowermost article are supported, a resiliently mounted plunger adjacent the bottom of said magazine and adapted to push the bottom article from one of said shelves, said magazine including end walls terminating above said shelves to present apertures, through one of which an end of the lowermost article extends when same is pushed off one of its supports, said plunger being axially slideable in said other aperture and having an inclined end portion adapted to raise and support the articles above the lowermost one while the latter is pushed off one of its supports.

3. A device of the character described comprising a magazine substantially open at the bottom and in which articles may be vertically stacked, spaced means adjacent the bottom of said magazine for supporting the articles at their ends, said magazine comprising spaced guide channels including end walls terminating above said article supporting means to present apertures, through one of which an end of the lowermost article extends when the article is pushed off one of its supports, a resiliently mounted plunger operating in said other aperture and adapted to push the bottom article from one of its supporting means, said other supporting means comprising a resilient shelf adapted to hold the corresponding end of the lowermost article in suspension.

JOSEPH A. DIEMER.
